UNITED STATES PATENT OFFICE.

WILBUR S. GREGORY, OF PORT JERVIS, NEW YORK.

LOCOMOTIVE-FEED-WATER HEATER.

Application filed September 11, 1924. Serial No. 737,181.

To all whom it may concern:

Be it known that I, WILBUR S. GREGORY, a citizen of the United States, residing at Port Jervis, in the county of Orange and State of New York, have invented certain new and useful Improvements in Locomotive-Feed-Water Heaters, of which the following is a specification, reference being had to the accompanying drawings.

10 This invention relates to accessories for use in connection with steam locomotives and has for its object the provision of a novel feed water heater utilizing the exhaust steam as the heating medium and embodying a 15 novel pumping system whereby the cold water is taken from a storage tank, passed through the heating device, and subsequently forced into the boiler.

Another object is the provision of an apparatus of this character embodying a triple pump arrangement, the members or elements of which are arranged in tandem and located at the bottom portion of the locomotive tender, the pumping mechanism being operated by live steam from the boiler.

A further object is the provision of an apparatus of this character in which the hot water pump is always full of water and consequently ready for instant service upon starting of the pumping mechanism.

Yet another object is the provision of a novel and peculiar heating device so constructed and arranged that the maximum heating power of the exhaust steam is utilized to bring the water up to the desired temperature.

The invention further contemplates the provision of an apparatus of this character embodying the above and still other features which constitute a distinct improvement and refinement in devices of this general character, the construction being, moreover, comparatively simple and inexpensive to manufacture and install, positive in action, efficient and durable in service, and a general improvement in the art.

With the above and other objects and advantages in view, the invention consists in the combination and arrangement of parts to be hereinafter more fully described and claimed and illustrated in the accompanying drawings in which:

Figure 1 is a phantom elevation of a loco-

motive tender and a fragment of a locomotive showing my device in applied position. 55

Figure 2 is a sectional view through my device alone, parts being broken away and portions being in elevation.

Figure 3 is a detail cross section through the heating device. 60

Referring more particularly to the drawings, the letter A designates a steam locomotive, B represents the tender therefor, C the exhaust steam line, D the live steam line, E the boiler feed pipe, and F indicates a water 65 storage tank.

In carrying out the invention I provide a heating device comprising a casing 10 mounted at the top of the tender and having the exhaust steam pipe C connected or communicating with its top. In this casing is a vent 11 and an opening 12 permitting access to the interior, which hole is normally closed by a cover plate 13. Located within the upper portion of this casing is a water conducting pipe 14 terminating in a spray nozzle 15 and fed with water by means to be described. 70

Secured to and extending downwardly from the lower forward portion of the casing 10 and arranged in an inclined direction, is a conduit 16 of any desired size, shape and material but which is here represented as rectangular in cross-section as such a form is quite convenient. The interior of this conduit communicates with the bottom 75 of the casing 10 through an opening 17 located in position to receive water discharged from the spray nozzle 15. Located within this conduit and spaced from the back wall thereof, is a partition 18 defining a passage 80

19 into the upper end of which leads a pipe 20 connected with the exhaust steam pipe C, as shown. Secured on the forward face of the partition 18 are superposed baffle plates 21 which terminate short of the other side or front of the conduit, and beneath the series of baffles the partition 18 is provided with holes 22 which will permit exhaust steam within the passage 19 to pass out beneath the successive baffles, and this steam, together 85 with the steam entering the casing 10 through the pipe C will act upon the water sprayed from the nozzle 15 and effect heating of the water to a sufficiently high temperature that it will be ready for introduction to the boiler. 90

100

105

In conjunction with the above apparatus, I provide a pumping mechanism located at the lower portion of the tender B. This mechanism includes cylinders 23, 24 and 25 arranged in tandem or in horizontal axial alinement. The cylinder 23 contains a piston 26 on a piston rod 27 which is common to all three cylinders and which carries pistons 28 and 29 operating within the cylinders 24 and 25, respectively. The cylinder 23 carries a conventional steam chest 30 with which the steam pipe D is connected, an oil separator or filter 31 being interposed in the line. Within the chest 30 is any ordinary or preferred type of slide valve, not shown, provided for the purpose of supplying steam pressure alternately to opposite sides of the piston 26 for moving the piston rod 27 and consequently the pistons 28 and 29 carried thereby.

At the top and bottom of the cylinder 24 are passages 32 and 33, respectively, the former of which is connected by a pipe 34 with the water storage tank F, and the latter of which has leading therefrom a pipe 35 leading to the casing 10 and connecting with the pipe 14 therein. The cylinder 24 is equipped with inlet valves 36 and outlet valves 37 whereby reciprocation of the piston 28 will cause water entering the passage 32 from the tank F to be drawn into the cylinder at each stroke of the piston and to be forced out through the valves 37 into the passage 33 and thence through the pipe 35 to the spray device in the casing 10.

The cylinder 25 is provided at its top with an inlet passage 38 having an opening 39 communicating with the lower end of the conduit 16 so as to receive the water heated in the conduit by means of the exhaust steam. It should be mentioned that the exhaust steam condenses and mixes with the water so that any excessive pressure is avoided. At the bottom of the cylinder 25 is an outlet passage 40 with which the feed water pipe E is connected. Obviously, flexible hose members or other similar devices are provided wherever necessary and no claim is made to their employment as they are old and well known in the art. The cylinder 25 is equipped with inlet valves 41 and outlet valves 42 whereby upon every back and forth stroke of the piston 29 water will be drawn into the cylinder from the passage 38 and be forced into the passage 40 and out through the feed water pipe to the locomotive.

Leading from the passage 32 of the cylinder 24 is a pipe 43 leading into the inlet passage 38 of the cylinder 25 and containing a ball check valve 44 for the purpose of preventing back pressure. The purpose of this transfer pipe is to permit feed water to pass from the cylinder 24 to the cylinder 25 even when the pumping mechanism

is not in operation, the advantage being that the cylinder 25 always contains a supply of water ready to be fed to the locomotive. It should also be stated that the cylinders 24 and 25 are provided with upstanding vent pipes 45 and 46, respectively, which terminate above the maximum water level in the tank F. The lower end portion of the conduit 16 may be provided with a movable door 47 permitting access to the interior for the purpose of cleaning out any matter therein or for any other necessary reason.

From the foregoing description and a study of the drawings it will be apparent that I have thus provided a simply constructed, inexpensive and easily installed feed water supply system for locomotives embodying novel heating means in combination with a peculiarly arranged pumping mechanism which will insure proper action and an automatic feed at all times. Owing to the fewness of the parts it is apparent that there is very little to get out of order so that the device should have a long and satisfactory life.

While I have shown and described the preferred embodiment of my invention, it is of course to be understood that I reserve the right to make such changes in the form, construction, and arrangement of parts as will not depart from the spirit of the invention or the scope of the subjoined claims.

Having now described my invention, what I claim as new and desire to secure by Letters Patent, is:

1. In combination with the exhaust steam line, water supply tank, and boiler feed pipe of a locomotive, a tandem pump mechanism receiving water from the storage tank, a heating device connected with the exhaust steam line, spray means within the heating device connected with the pumping mechanism, and an outlet connection from the pumping mechanism to the boiler feed pipe, and a check valve transfer pipe between elements of the tandem pumping mechanism for permitting flow of water therethrough.

2. The combination with the feed water tank, boiler feed pipe, live steam line and exhaust steam line of a locomotive, of a pump receiving from said tank, a heating casing and conduit in communication with the exhaust steam line, a spray nozzle within the casing connected with the pump and receiving water therefrom, means operated by the live steam line for operating said pump, and a second pump having a check valve communication with the first named pump and receiving from the heating conduit, and discharging into the boiler feed pipe.

3. In an apparatus of the character described, exhaust steam operated water heating means comprising a casing, an exhaust

steam pipe connected therewith, a water spray nozzle within the casing, means for supplying water to the nozzle, an inclined conduit connected and communicating with the bottom of the casing and having a passage member extending throughout the length thereof, a series of stepped baffles on the passage member, and the passage member having a plurality of openings communicating with the conduit beneath the successive baffles.

In testimony whereof I hereunto affix my signature.

WILBUR S. GREGORY.
